UNITED STATES PATENT OFFICE.

HENRY S. WIKEL, OF YORK, PENNSYLVANIA.

RAIL-JOINT.

1,111,630.

Specification of Letters Patent. Patented Sept. 22, 1914.

Application filed January 28, 1914. Serial No. 815,039.

To all whom it may concern:

Be it known that I, HENRY S. WIKEL, a citizen of the United States, residing at York, in the county of York and State of Pennsylvania, have invented new and useful Improvements in Rail-Joints, of which the following is a specification.

The present invention relates to means for connecting the meeting ends of two railway rails in such a manner as to reinforce the rails at the joint, as well as to prevent the tilting, sagging, or creeping of the joint. I attain these objects, and others which will appear as the nature of the invention is more fully understood by the construction, combination and arrangement of parts disclosed by the accompanying drawings, set forth in the following specification and falling within the scope of the appended claims.

The drawings illustrate a simple and satisfactory reduction of the improvement to practice, but the important instrumentalities thereof may be varied, and so the showing is to be considered merely illustrative and I am not to be restricted to the precise details of construction set forth therein.

In the said drawings: Figure 1 is a side elevation illustrating two rails connected in accordance with the present invention, Fig. 2 is a top plan view of the same, Fig. 3 is a bottom plan view of the same, Fig. 4 is a transverse sectional view on the line 4—4 of Fig. 1, Fig. 5 is a detail sectional view through the bolt provided to engage the webs at the meeting ends of the rails, the fish plate or rail chair being broken away, Fig. 6 is a view looking toward the inner face of one of the chair members, Fig. 7 is a side view of a modified form of the joint, Fig. 8 is a transverse sectional view through the same, and Fig. 9 is a view looking toward the inner face of one of the rail chair sections.

When a train travels upon a track between the joints in the rails the revolving of the wheels upon the rails has a tendency to slide the said rails, and as a consequence the joint plates are under constant vibration, and as a result, the securing nuts and bolts become loosened and the plates disconnected from the rails. The rails, under such conditions, are liable to be pulled one away from the other, and it is not infrequent that such a movement causes one of the rails to be either depressed or elevated above the second rail, so that the rail ends at the joint

are not flush which causes the wheels of the rolling stock to contact with the abrupt projecting rail end, inflicting injury not only to the rail end, but also to the wheels of the 60

It is my purpose to construct a joint which will effectively overcome the above defects, as well as the liability of the tilting or inclination of the rails at the joint, and in the accompanying drawings, I have shown two rails, designated by the numerals R—R, connected in accordance with my invention.

In constructing my joint I employ a chair which is made up of two sections or members, which are of a similar construction, and each being designated by the numeral 1. The joint chair is of a length sufficient to receive at least four of the ties T, and each of the sections includes a base 2 which is horizontally straight and which is adapted to receive the base flanges of the rails R. Each of the base members 2 is provided at its inner edge with a downturned flange 3, the same extending the entire length of the member 1, and the base 2 of each of the said members 1 at a suitable distance from its outer longitudinal edge is formed with a vertically projecting wall 4 which joins the outer terminal of an angular flange 5 which overlies the base flange of the rails R, the said overlying flange 5 terminating in a vertical plate or wall 6. The wall 6 has its central portion, for the major portion of its length, horizontally straight, and adapted to underlie and support the heads of the rails R, while the said upper edge from the central portion thereof is inclined in opposite directions to the ends of the vertical plate, as clearly shown in the drawings. 90

The inner upper edge of the plate 6 is provided with a bead 7 which follows the shape of the upper edge of the said plate and which abuts with the webs of the rails, while each of the said plates 6 at its connection with the overlying flange 5 is formed with a second bead 8 which extends the entire length of the plate and which abuts with the rails at the juncture of their base flanges and webs. As the bead 7 greatly 100 enlarges the width of the plate 6 at the upper edge thereof I have found it desirable to bevel the outer edge at the corner of the said upper plate, the said beveled portion being indicated by the numeral 9, and by 110 cutting away the metal at this point, a desired amount of resiliency is afforded the

upper beaded edge of the plate, as will readily be understood. Each of the plates 6 is provided with a plurality of transverse openings, each of said openings being adapted for the reception of the usual securing bolts 10 which pass through registering openings in the webs 11 of the rails, the threaded ends of the said bolts receiving the usual securing nuts 12. I have also found it desirable to notch the meeting ends of the rails centrally of the webs thereof, as indicated by the numerals 13, the said notches, when brought into register, providing a rectangular opening which registers with a similar opening 14 in each of the vertical members or plates 6 of the rail chair sections 1.

The numeral 15 designates a bolt having a rectangular shank and a rounded threaded extension, the same corresponding to the shape of the registering notches 13 and contacting with the walls thereof when the said bolt is inserted through the openings 14. The threaded extension of the shank is engaged by a nut 16, which is of a size sufficient to fully close the openings 14 upon the side of the plate with which it contacts.

The projecting edges and the corner of the said projections are beveled or rounded, as at 18, to correspond with the underfaces of the spikes 19 which engage therewith and which enter the ties T.

The vertical downwardly extending flanges 3 terminate a suitable distance apart, and these flanges 3 are arranged upon the base members 2 at suitable spaced intervals, three of the said flanges being shown, in the present instance, upon each of the rail chair members, the distance between the said flanges 3 being equal to the width of the ties T, so that the ends of the said flanges 3 will contact with the said sides of the ties, and the end flanges 3 terminate a distance slightly less than the width of the ties upon which the ends of the said chair rest. The flanges 3 of the sections 1 are provided with registering openings for the reception of securing elements in the nature of bolts 20 and nuts 21 therefor. The extensions 17 at the ends 50 of the joint chair sections are provided with extensions or ears 21, the same being provided with suitable openings for the reception of securing elements 22 which enter the ties upon which the ends of the joint chair is supported. These ears 22 perform a function in combination with the flanges 3, which, as stated, engage with the opposite sides of the ties, that is one of the essential features of the present invention, the same being to absorb or cause the joint to withstand the initial force of impact or stress from the wheels of the rolling stock contacting with the rail before the same passes over the joint or over the chair and so a joint constructed in accordance with my invention

effectively overcomes such a movement of the rails, as the joint cannot be moved nor can either of the rails connected therewith be moved longitudinally without moving the ties T, and the said ties being embedded within the roadbed afford ample resistance to overcome such a movement. The plates 6 are in the nature of strut braces, and the heads of the rails bearing upon the central portions thereof and directly over the beads 7, the said plates afford a desired amount of resiliency or flexibility so that the rolling stock will not inflict injury to the meeting ends of the rails or to the joint.

In Figs. 7, 8 and 9 I have illustrated a slightly modified form of the joint. In these figures the members 1', which comprise the joint chair, have their base portions and their ends similar to the construction just described, the base members 2' being also provided with the vertical flange 4', having the overlying flange 5' and the vertically extending side or plate 6'. The sides or plates 6' have their upper edges enlarged, as indicated by the numerals 50. The enlarged edges project laterally of the plate 6', so that both the inner and outer edges of the said portions 50 are formed with what may be termed beads, the inner member of which being similar to the bead 7 in the structure previously described. The upper face of the enlargement 50 of each of the members 6' is beveled or inclined to correspond with the shape of the underfaces of the rails which rest upon the said portions 50. The plates 6' at their juncture with the overlying flanges 5' are formed upon their inner faces with beads 51, corresponding with the beads 8, and I have also found it desirable to provide the said inner faces of the plate 6' with centrally longitudinally extending inturned members or beads 52. The securing elements for the base are in the nature of spikes, the said base and its end extending members 21' being arranged upon ties in a similar manner and secured upon the said ties as previously set forth. The plates 6' are provided with transverse openings which may intersect the beads 52 or which may be arranged in the channeled face of the plate 6' between the upper and lower beads, the said openings registering with similar openings in the webs of the rails and being provided with the ordinary bolts and nuts therefor.

From the above description, taken in connection with the accompanying drawings, the simplicity of the device as well as the advantages thereof will, it is thought, be perfectly apparent to those skilled in the art to which such invention appertains without further detailed description.

Having thus described the invention, what I claim is:

1. In combination with the meeting ends

of two rails and a plurality of ties for the rails, of a joint chair for connecting the rail ends, said chair comprising two companion sections, each of which includes a base upon which the rails rest, the inner edge of each of the base portions having a plurality of downturned flanges of a length to be received between the ties and to contact with the sides of the ties, means for connecting the said flanges, each of the chair members also including an inturned angular flange which overlies the base flanges of the rails, and a vertical plate which is integrally formed with the overlying flange, 15 said plate having its upper edge for the major portion of its length of a height to engage beneath the heads of the rails, and the said plate being inclined from the said central portion to its ends, means for securing the plates to the webs of the rails, means for securing the chair sections to the ties, each of the chair sections having its longitudinal edge, at its ends, provided with an outwardly extending ear, and means for securing the said ears to the end ties for the joint chair.

2. In combination with the meeting ends of two rails and a plurality of ties for the rails, of a chair connecting the rail ends, 30 said chair comprising two companion members, each of which including a base upon which the rails rest, the inner longitudinal edge of the base having spaced downturned flanges which are adapted to be arranged 35 between the ties and to contact with the sides of the tie, means for connecting the flanges, the base members, at a distance from their longitudinal edges having inturned flanges which overlie the base flanges 40 of the rails, the said longitudinal edges at the ends of the chair sections being formed with outwardly extending flat members, means for securing the said flat members to the end ties upon which the chair rests, 45 means co-acting with the longitudinal edges of the chair sections for securing the same to the intermediate tie, the overlying flange of each of the sections being integrally formed with a vertical plate which is adapted 50 to abut with the opposite faces of the webs of the rails, each of the said plates, for the major portion of its length, having its upper edge of a height to underlie the heads of the rails, and the said plate being in-

clined from the said central portion to its ends, the inner face of the plate at its said upper edge being formed with a continuous bead which corresponds with the shape of the said upper edge and which extends inwardly of the plate a distance approximately equaling the distance between the outer longitudinal edges of the heads and the webs of the rails, the lower inner faces of the plates at their juncture with the overlying flanges being provided with longitudinally extending beads, and means intermediate the beads for securing the plates to the webs of the rail.

3. In combination with the meeting ends of two rails and a plurality of ties for the rails, of a chair for securing the rail ends, said chair comprising a pair of companion sections, each including a base upon which the rails rest, and each of the said base portions being of a less width than one-half of the thickness of the base portions of the rails, the inner longitudinal edges of the said base portions of the chair having a plurality of downturned flanges which are adapted to fit between the ties and to engage with the sides of the ties, overlying flanges connected adjacent the outer longitudinal edges of the bases and overlying the base flange of the rails, the said outer edges of the base members at the ends of the chair having laterally extending plates which rest upon the end ties of the chair, means for securing the said members to the said end ties, means contacting with the outer longitudinal edges of the base member for securing the chair to the intermediate ties, vertical plates formed with the overlying flanges, said vertical plates having their upper edges formed with beads and underlying the heads of the rails and conforming to and underlying the heads of the rails, the inner faces of the said plates being provided with a plurality of spaced longitudinally extending beads which contact with the webs of the rails, and means for securing the said plates to the webs of the rails.

In testimony whereof I affix my signature in presence of two witnesses.

HENRY S. WIKEL.
